RIDING HORSE

Laurie Jay Campbell, Erie, Pa., assignor to Louis Marx
& Co., Inc., New York, N.Y., a corporation of New
York

Filed Apr. 27, 1967, Ser. No. 6,857

Term of patent 14 years

(Cl. D34—15)

FIG. 1

FIG. 2

FIG. 3

FIG. 4

FIG. 5

FIG. 6

FIG. 1 is a side elevational view of a riding horse of my new design;

FIG. 2 is a top plan view thereof;

FIG. 3 is a front view thereof;

FIG. 4 is a rear view thereof;

FIG. 5 is a bottom plan view thereof; and

FIG. 6 is a view similar to FIG. 1 showing the riding horse in the fully extended position.

The dominant feature of my new design resides in a riding horse having a body with laterally spread legs in which the body has a general overall contour provided by sharp-angled lines which are specially pronounced at the rear part of the body, all as shown.

I claim:

The ornamental design for a riding horse, as shown and described.
